DRILLING BORE HOLES

Benjamin W. Sewell, Tulsa, Okla., assignor to
Standard Oil Development Company, a corpora-
tion of Delaware

Application August 7, 1947, Serial No. 766,934

2 Claims. (Cl. 255—24)

1

The present invention is directed to a method and apparatus for drilling bore holes, and more particularly to a method and apparatus which permits a continuous coring of the formation penetrated by the bore hole.

In the conventional rotary drilling process a hollow drill pipe carrying a drill bit is caused to penetrate the earth while maintaining a circulation of drilling fluid downwardly through the inside of the drill pipe, out through suitable eyes in the drill bit and up through the annular space between the drill pipe and the borehole wall to the surface where it is discharged into a pit for the settling of cuttings. This drilling fluid is then pumped from the setting pit to the upper end of the drill pipe. This method of drilling, by reason of the direction of circulation of the drilling fluid, makes it impossible to obtain continuous cores of the formations penetrated. Moreover, in this method the upward flow of drilling fluid through the annular space mentioned above frequently develops rather high velocity which tends to cause sloughing of the bore hole wall.

According to the present invention the rotary drilling method is improved, first, by reversing the direction of flow of the drilling fluid so that it flows downwardly through the space between the drilling pipe and the borehole wall and upwardly through the drill stem. This in itself is not a new expedient. In previous embodiments, however, the circulation of the drilling fluid has been a forced circulation induced by applying pressure to the mud column in the annular space. This pressure tends to accelerate filtration of the fluid into porous formations and also to increase lost returns. According to the present invention these difficulties are avoided by merely maintaining the annular space full of fluid and inducing circulation by aerating the mud column inside the drill pipe for an appropriate distance below its top to create the necessary differential in pressure head between the columns outside and inside of the drill pipe to cause flow upwardly through the drill pipe.

The principal object of the present invention is to provide a rotary method for drilling bore holes in which the conventional flow of fluid is reversed with the column of fluid outside the drill stem existing under its own hydrostatic pressure.

An additional object of the present invention is the provision of a method and apparatus of the character described in which provision is made for the collection of a limited number of cores during the drilling operation, which cores may be brought to the surface.

2

A more specific object of the invention is the provision of a method and apparatus of the character described by which a bore hole may be drilled and continuous cores of the formations penetrated brought to the surface and recovered without interrupting the drilling operation.

A more specific object of the present invention is the provision in apparatus of the character described of means for breaking up a continuous core into relative short sections so that they may readily flow to the surface.

Further advantages of the present invention will appear in the following detailed description of the accompanying drawing, in which

15 Figure 1 is a vertical section of a bore hole with an embodiment of the present invention in operative position and partly in section;

Figure 2 is a similar view of a modified form of the present invention;

20 Figure 3 is a similar view of still another embodiment of the present invention;

Figure 4 is an enlargement of A— of Figure 3; and

25 Figure 5 is a vertical section of an alternative form of the arrangement shown at the bottom of the drill stem in Figure 3.

Referring to the drawing in detail, numeral 1 designates the earth penetrated by a bore hole in which is arranged a drill stem 2 carrying a conventional drill bit 4. The upper end of the drill stem is provided with the usual Kelly 5 having a swivel joint 6. It will be understood that the Kelly is a pipe of non-circular cross section and passes through a correspondingly shaped hole in the rotary table. The swivel joint above the Kelly is provided with the usual line 7 which in this case is used to conduct drilling fluid into the mud pit instead of passing it down through the drill stem. Extending down into the drill

30 stem is a pipe 8 which at its lower end is provided with a distributing head 9. This pipe extends down into the drill stem a distance selected to give a rate of flow desired in the circulating drilling fluid stream. In other words the higher the

35 rate desired, the farther down into the drill pipe this line 9 is extended. The drilling mud is returned from the mud pit to the annular space between the bore hole and the drill stem by a pipe 10 which ordinarily can be an open ended pipe 40 discharging into said annular space at a rate sufficient to keep said space full of drilling fluid.

In operating according to the present invention, the annular space and the drill pipe are filled with drilling fluid and circulation is started 45 by starting the flow of gas through pipe 8. The

velocity of flow of the gas for a given position of the pipe 8 and for a given drilling mud will determine the rate of circulation of drilling mud. Thus the operator has two controls over this rate of circulation. For best results, according to the present invention, it is preferred that the viscosity of the fluid be adjusted to between about 10 and 30 centipoises and that its gel strength be maintained at a sufficiently low level to readily release the gas introduced through line 8 when it is discharged into the mud pit. It will be appreciated that the drilling mud can be constantly or periodically treated with chemicals commonly called deflocculating or peptising agents such as sodium tannate, sodium phosphate, sodium pyro-phosphate, sodium metavanadate and the like which tend to hold down or reduce the viscosity of the drilling fluid so that it will readily release gas.

In the embodiment shown in Figure 2 the drill stem is provided at its lower end with a core receptacle 11 at the upper end of which is a stop 12 having suitable passages 13 for the circulation of the drilling fluid. In this case the drill bit 14 employed is a conventional core bit adjacent to which the core receptacle is provided with a core catcher 15. This core receptacle may be made any desired length depending upon the thickness of the section that is to be cored.

In the embodiment shown in Figure 3 parts corresponding to those shown in Figure 1 bear the same numeral. This embodiment is designed for continuous coring while using the gas-lift principle. To achieve this objective the upper end of the drill stem 3 is provided with a plurality of sections 16 each of which is composed of two concentric pipes. The inner-pipe 17 has the same diameter as the drill stem, which in this case should be uniform from the surface substantially to the drill bit. The outer pipe is spaced from the inner-pipe a distance sufficient to provide a passage for gas. In the lowermost section 16, conduits 18 connect the annular gas passage 19 with the inside of the inner-pipe 17. These conduits 18 are spaced from each other peripherally so that a suitable number of inlet ports is provided in the inner-pipe 17 to insure fairly uniform distribution of the gas in said pipe. The abutting ends of the sections 16 are likewise provided with peripherally spaced conduits 20 which serve to conduct gas from one annular space 19 to another. One of these abutting ends is provided with an annular channel 21 forming a sort of manifold with which the conduits 20 in the abutting ends connect so that actual alignment of these conduits is unnecessary.

In this embodiment as indicated above, the inner bore of the drill stem should be uniform substantially throughout its length. In order to facilitate the floating of the cores to the surface, there is provided near the end adjacent the core bit 22 a wedge-like member 23 affixed to the inner-wall of the drill stem having its pointed end downward. As the core 24 moves upwardly in the drill stem, its upper end slides along the inclined plane formed by the wedge member which has an inclination such as to cause a portion of the core to break off as its upward movement continues.

In Figure 5 is shown a modified form of the arrangement for breaking up the core into short lengths. In this case there is arranged in the drill stem 3 as a continuation of the central passage of the core bit 22 a bent pipe 25. As the

core moves upwardly through this pipe, it is deflected from the vertical in such a manner as to break into segments of appropriate lengths. Upon leaving this pipe the segments of the core pass upwardly through the drill stem.

At the upper end of the drill stem in the continuous coring embodiment there is connected to the swivel 6 a goose-neck 26 which discharges drilling fluid and core segments from its open end onto a screen 27 arranged in a vessel 28 and spaced from the bottom thereof whereby drilling fluid passing through such screen may leave the vessel by conduit 29 which discharges into the mud pit.

Gas for the lifting of the drilling mud is admitted into the annular chamber 19 by a duct 30 connected to a swivel gland 31 on which the flange 32 on the upper end of the outer pipe of the uppermost sections 16 rests. The swivel gland in turn rides on a flange 33 carried by a collar connected to a packing gland 35 mounted on the drill stem.

As previously indicated, in the practice of the present invention, one can employ as many sections 16 as desired. The uppermost sections 16 including the swivel air gland and the packing gland may be a very short section which remains permanently attached to the Kelly and to which other sections of the drill stem are added as needed. Usually the first few sections of drill stem added are of the type forming the lower portion of the drill stem without the annular gas chamber. As soon as the top 60 to 80 feet are drilled, a section corresponding to the lowermost sections 16 is included in the stem, and circulation of the drilling fluid by gas lift begun. It is clear, of course, that this can be started earlier.

It will be appreciated that the method and apparatus of the present invention are susceptible to many changes without undergoing any change in essential character. This invention provides not only the considerable advantages heretofore listed of avoiding difficulties usually attending reverse flow circulation of drilling fluid, but in addition eliminates the need for large expensive mud pumps. In view of the fact that the method of the present invention does not depend to any great extent on the viscosity of the drilling fluid for the lifting of cuttings and cores, it is desirable to utilize a drilling fluid having a strong suspending power, such as, one including a highly colloidal clay. If desired, the lifting action of the drilling fluid may be augmented by utilizing a wellhead and applying a small amount of pump pressure to the mud fed into the annular space between the drill stem and the bore hole wall. In addition mechanical de-aerators may be employed at the surface for facilitating the removal of the gas from the mud. Conventional weighting agents and other mud addition agents may be used in the practice of the present invention.

The nature and objects of the present invention having been thus described and illustrated, what is new and useful and is desired to be secured by Letter Patent is:

1. A drilling apparatus for the continuous coring of earth formations encountered in drilling a borehole comprising an upper portion of drill stem consisting of a plurality of threadedly combined gas conducting drill pipe sections, each section being composed of two concentric pipes defining between them an annular passage for gas, solid ring portions joining said concentric pipes at their ends and closing off said annular

passage, at least one of said ring portions being provided with an annular groove on its exposed side, peripherally spaced conduits extending through said ring portions longitudinally of said concentric pipes and in substantial alignment with said annular grooves so that the spaced conduits in abutting gas conducting drill pipe sections will communicate with said annular grooves, a lowermost gas conducting drill pipe section provided with a plurality of ports substantially uniformly spaced peripherally in the wall thereof and establishing communication between the annular groove in the end of the abutting gas conducting drill pipe section and the central bore of said lowermost gas conducting drill pipe section, a lower portion of drill stem comprising conventional drill pipe attached to said lowermost gas conducting drill pipe section, a core bit attached to the lower end of said conventional drill pipe, a core-breaking wedge member affixed to the inner wall of said conventional drill pipe at a point intermediate said core bit and said lowermost gas conducting drill pipe section, means for introducing gas into the annular gas passage in the uppermost of said gas 25

10

5

conducting drill pipe sections, and means for introducing a liquid into the annulus between said drill stem and the walls of the borehole.

2. Drilling apparatus according to claim 1 including means for regulating the pressure of the gas introduced into the annular gas passage and thereby regulating the rate of upward flow of liquid through the center of the drill stem.
